Primary Examiner — Anhdao Doan(74) *Attorney, Agent, or Firm* — Knobbe Martens Olson & Bear LLP(57) **CLAIM**

The ornamental design for a medical device electronic module, as shown and described.

DESCRIPTION

FIG. 1 is a top perspective view of an embodiment of a medical device electronic module;

FIG. 2 is a bottom perspective view of the electronic module of FIG. 1;

FIG. 3 is a front view of the electronic module of FIG. 1; FIG. 4 is a rear view of the electronic module of FIG. 1; FIG. 5 is a right side view of the electronic module of FIG. 1;

FIG. 6 is a left side view of the electronic module of FIG. 1;

FIG. 7 is a top view of the electronic module of FIG. 1; and, FIG. 8 is a bottom view of the electronic module of FIG. 1. The broken lines illustrate portions of the medical device electronic module that form no part of the claimed design.
